UNITED STATES PATENT OFFICE.

EDWARD J. FOWLER, OF REDWOOD CITY, CALIFORNIA, ASSIGNOR TO NICHOLS COPPER COMPANY, OF NEW YORK, N. Y., A CORPORATION OF NEW YORK.

FURNACE RABBLE ARM.

Application filed March 19, 1927. Serial No. 176,592.

This invention relates to furnace rabble arms, as for example rabble arms for multiple hearth rotating shaft furnace constructions.

5 The objects of this invention include the provision of improved rabble arms, rabble teeth, and associated parts of an inexpensive and durable construction, which preferably are made to be readily demountable as for 10 rapid repair and replacement. Furthermore, constructions embodying this invention in most instances make possible a substantial saving in the materials necessary therefor, and also a saving in the number of 15 necessary parts. Rabble arms embodying this invention may be readily applied to various existing types of furnace constructions substantially without alterations to such furnaces.

20 The invention consists in the novel features, arrangements and combinations of parts embodied by way of example in the apparatus hereinafter described as illustrating a preferred form of the invention, and 25 various specific objects, features and advantages of the invention will more clearly appear from this description taken in connection with the accompanying drawings.

In the drawings, Fig. 1 represents a vertical sectional view partly broken away and 30 taken substantially along the vertical axis of a furnace embodying the invention.

Fig. 2 is a top or plan view, partly in section, showing a rabble arm and adaptor member therefor embodying certain features 35 of the invention.

Fig. 3 is an elevational view, partly in vertical section, showing a rabble arm and adaptor member embodying features of the 40 invention and attached to a rotatable furnace shaft;

Fig. 4 is a view similar to Fig. 3, but showing a portion of the rabble arm in vertical section and also showing an adaptor member which is of a length greater than the adaptor member of Fig. 3 for a purpose 45 hereinafter set forth;

Figs. 5, 6 and 7 respectively are transverse sectional views of the rabble arm and adaptor members taken substantially along the section lines 5, 6 and 7 of Fig. 3;

Fig. 8 is a longitudinal sectional view taken substantially along the line 8—8 of Fig. 3;

Figs. 9 and 10 respectively are top and side views showing a rabble tooth embodying features of the invention; and

Figs. 11-16 inclusive are longitudinal and transverse sectional views showing the invention in certain of its phases for application to furnace constructions of other various types.

The furnace as shown in Fig. 1 is of a conventional type having a plurality of vertically spaced or superposed and substantially circular hearths as at 21, 22, 23 and 24. These hearths are surrounded and supported in the usual manner as by a substantially cylindrical furnace wall 25. A rotatable and internally cooled central shaft 26 extends vertically up through the furnace substantially along the central axis thereof for supporting a number of rabble arms extending radially from the shaft into the spaces between succeeding hearths. Rabble teeth 75 are provided on each of the rabble arms for stirring and advancing the material being treated successively over each of the hearths.

The common practice has been to provide a series of rabble teeth on each arm, the arm being formed with a suitable longitudinal slot for receiving the numerous rabble teeth accompanied by spacer members. By the use of spacer members, the teeth are spaced along the length of the arm so that over each hearth the respective paths of travel of the teeth on the several arms for that hearth will be interspaced, thus giving a uniform rabbling action over the area of the hearth. However, with such construction, 80

in order to replace broken or worn out teeth, it is sometimes necessary to first successively remove each of a long series of teeth and spacer members before the broken tooth can be reached, since the teeth are all arranged 85 in succession within a single slot extending the length of the arm. The removal of such an arm as a whole with the teeth attached is a difficult alternative, because of the length of the arm and its great weight when equipped with the numerous teeth and spacer members. Furthermore, in setting up furnaces of the conventional types heretofore used, separate attention must be given 90 to the proper positioning of each of the numerous teeth in order to attain the desired interspacing of the paths of travel of the teeth on the several arms.

The construction about to be described substantially eliminates these difficulties and also embodies additional advantages.

The invention herein relates more particularly to certain novel features of construction embodied in the rabble arms and associated parts and, accordingly, as to the design and constructional details of other parts of the furnace not specifically referred to herein, the usual practice may be followed as carried out in the construction of other well known furnaces of this general type.

As indicated in Figs. 2-8 inclusive, a rabble arm is provided having two substantially concentric tubular members 27 and 28, the outer member 27 forming a support or body member for carrying the rabble teeth and the inner member 28 comprising a conduit for controlling the circulation of cooling fluid within the arm. It will be noted that the outer member has a cross-section substantially larger than the inner member and that the two members are thus spaced apart by an annular passageway 29, which receives the circulating cooling fluid. The tubular member 27 may be provided at 30 with a relatively narrow bearing area, which encircles the member and is designed to be fitted into a corresponding bearing portion formed upon a furnace rabble arm adaptor member 31, (or 31^a as shown in Fig. 4), as hereinafter described. Beyond said bearing area the tubular member 27 is extended and formed with a relatively restricted or substantially conical end portion 32, which is tapered down to such a diameter that its peripheral edges at 33 closely embrace and may be joined to the corresponding peripheral edges at the inner end of the conduit 28 (see Figs. 4 and 8). The inner end of the conduit is thereby securely held in position with its walls substantially concentric with the outer tubular member. Except for the inner end of the conduit 28, its walls are thus substantially spaced from the body member of the rabble arm and accordingly uniform heat radiation and cooling of the inside walls of the rabble arm are not interfered with by the bearing parts nor by the presence of the conduit. It will be noted that the conduit joins the outer tubular member at a point wholly within the limits of the walls of the adaptor member and accordingly the joint is protected from the high temperatures prevailing within the furnace. The restricted or conical portion 32 may be formed with suitable large perforations or openings as at 34 and 35 which provide passages permitting the cooling fluid to freely circulate from the annular passage 29 out of the rabble arm and into the passages of the adaptor member as hereinafter described. At the same time sufficient wall area remains in the conical portion 32 to provide ample strength.

The adaptor members 31 or 31^a may comprise an outer approximately cylindrical body member 36 formed at one end with a suitable flanged means 37 designed to be bolted as by bolts 38 in a conventional manner to a corresponding flanged portion 39, as provided upon the central rotatable shafts of many roasting furnaces of this general type now in use. At its outer end the adaptor member is formed with an annular bearing portion 40 for receiving the bearing area 30 above described. The rabble arm may be secured in position with the bearing portions 30 and 40 in engagement by means of a pin member 41 fitting into suitable aligned apertures extending through the two bearing portions. It will be noted that with the rabble arm in position the walls of the adaptor member are substantially spaced from the end portion of the rabble arm except at the narrow bearing area 40. The hollow adaptor member being filled with the circulating cooling fluid, a uniform cooling action over all of the portions of the joint area is insured. The walls of the adaptor member and of the rabble arm are preferably substantially free from reinforcing ribs, thickened areas, etc., which further contributes to the same result. The elimination of reinforcing ribs and the like not only results in a saving of material and reduction of weight, but also prevents non-uniform temperature conditions and the consequent destructive forces and strains which tend to arise within thick metal parts.

Within the adaptor member a cooling fluid conduit portion 42 may be formed, either integrally with the outer adaptor housing or as a separate part fitting therein. The central shaft of the furnace may be formed in sections as of cast iron and inside of each section and preferably concentric with the outer walls 43 a cooling fluid conduit as at 44 is provided. At each point where rabble arms are to be attached, the shaft sections are provided with one of the bearing areas 39. Also opposite each rabble arm the conduit 44 is provided with a branch extension 45 having openings within the limits of the bearing areas 39. The outer space within the adaptor member is designed to be communicative with the space between the shaft wall 43 and the conduit 44, whereas the conduit portion 42 within the adaptor is designed to be communicative with the conduit extension 45 and conduit 44. The conduit portion 42 in the adaptor terminates with a suitable opening or socket having a bearing area 46 for embracing the peripheral edges at the end of the rabble arm members. At the same time, this socket portion provides communication between the conduit portion 42 and the rabble arm conduit 28. With this construction two widely spaced bearings at 40 and 46 are provided for the

rabble arms and in view of this spacing, such bearings need be only narrow areas offering substantially minimum interference with the thorough cooling of the interior surfaces 5 of the adaptor member and rabble arms. At the same time this construction provides a durable interengaging plug and socket means between the adaptor and arm, whereby the arm is readily demountable after removing 10 the pin 41.

When the furnace is in operation with the central shaft assembled with its rabble arms, the path of the cooling fluid is from the interior of the shaft conduit 44 through the 15 extension outlets 45 into the adaptor conduit portions 42, thence into the rabble arm conduits 28 to the end of the rabble arms. The cooling fluid is then returned through the 20 annular space 29 in the rabble arm and a corresponding annular space 47 within the adaptor member and thence to the annular space inside the central shaft. With the construction as described, the openings 34 and 35, notwithstanding the demountable construction, 25 may be made of ample size to permit the fluid to freely flow therethrough and at the same time the dimensions of the various parts are kept within practical limits. Also, these constructional features provide 30 the substantially maximum possible interior wall area of each part directly exposed to the circulating cooling fluid and thus protected from overheating.

In Figs. 9 and 10 a rabble tooth is illustrated provided with a substantially vertically extending ore engaging area 48 supported at its upper edge upon the rabble arm by a mortise and tenon joint construction. The tenon portion as shown in Fig. 9 may 40 take the form of flange members 49 and 50 extending to either side of the plate 48 for engaging a corresponding mortise portion 51, the mortise portion being preferably cast integrally upon the under side of the rabble 45 arm body portion. It will be noted that each of the rabble teeth is thus individually and demountably secured to the rabble arm at a fixed position along the arm and that the mortise and tenon portions extend in the 50 general direction of travel of the teeth and are of increasing width toward the direction of travel, whereby a wedge-like engagement is obtained. That is, during the operation of the furnace, as the rabble teeth pass through the material being treated, the teeth will be either securely held, or if any slight movement takes place by reason of the forces exerted by the ore acting against the teeth, such movement will serve to bring the mortise and tenon portions into a firm wedging 55 engagement. Referring to Fig. 2, it will be observed that the rabble teeth nearer the supported end of the rabble arm are positioned at progressively increasing angles in 60 respect to the general direction of travel of

the teeth whereby proper rabbling is secured notwithstanding the possibility of using standardized teeth all alike. By thus using standardized teeth, manufacturing operations are greatly simplified and in addition, 70 the rabble arm assembly may be more quickly completed without danger of mistakes such as placing teeth having certain angles at improper positions.

When two or more rabble arms are used 75 in connection with a single hearth, it is desirable as above stated, to so position the rabble teeth along the arms that the respective paths of travel of the teeth on the several arms will be interspaced. Therefore, 80 each of the arms is to that extent preferably constructed differently. On the other hand, it is desirable for the reduction of the number of necessary spare parts and the manufacturing costs, to make all of the rabble arms 85 interchangeable and of a standard design. Accordingly, it has been the prevailing practice heretofore, in order to secure the desired interspacing of the paths of the rabble teeth, to provide means such as the 90 longitudinal channel above referred to and in which by suitable spacer members the teeth may be adjustably mounted in the desired positions. To eliminate the disadvantages of such an arrangement, according 95 to this invention each of the quick-detachable rabble arms with the rabble teeth individually mounted thereon may be made substantially alike but adaptor members of 100 different lengths and attached to the furnace shaft by the semi-permanent bolted joint may be provided for supporting the various arms with the rabble teeth at the desired radial distances from the central shaft to produce the interspacing referred to. For 105 example, if two rabble arms are provided for a single hearth, as is indicated in Fig. 1, then two adaptor members 31 and 31^a of different lengths may be used as indicated in Figs. 3 and 4. These two adaptor members 110 may be substantially identical in construction except for the lengths thereof and accordingly in the drawings like numerals are used to designate corresponding parts of these two members.

If desired, several rabble teeth may be mounted upon the adaptor member in a manner similar to the mounting of the rabble teeth upon the rabble arm itself. However, over hearths having large central openings, as hearths 22 and 24 in Fig. 1, rabble teeth on the adaptors may be unnecessary. Also the number of teeth on the adaptor member will of course be determined by the length of that member. As indicated in Fig. 4, the adaptor member may be of a substantial length as compared with the rabble arm itself, so that the arm and adaptor together may be described as a sectional rabble arm, 120 which in this instance is made up of two 125 130

sections joined end to end by the inter-engaging plug and socket portions. With such a sectional rabble arm, it is a simple matter to remove the outer section as a whole 5 together with the rabble teeth mounted thereon, whenever it is desired to repair or replace the arm, of any of the teeth. A spare arm of standard design already equipped with a full set of teeth in good condition may be 10 immediately inserted to replace the arm taken out. Thereafter at the operator's leisure, the broken or worn out teeth may be readily replaced individually without disturbing the teeth that are in good condition. 15 The time during which the furnace is out of working order is thus substantially minimized and only a single spare arm is necessary in view of the standardized construction.

According to this invention, if desired, 20 the adaptor member may be formed at one end with means of any one of several conventional types for engagement with the furnace shaft and formed at its other end with socket means of another conventional type 25 for receiving the outer rabble arm section. For example, the inner and outer wall members of the adaptor member may be formed at the furnace shaft end in a manner corresponding to the plug portion or inner end of 30 the rabble arm member per se. Also in another example shown in Fig. 11, a rabble arm member 52 is formed with an outer housing member 53 enclosing an internal cooling fluid conduit 54. At 35 and 56 respectively the members 53 and 54 are engaged by a socket portion of adaptor member 57, the adaptor member 57 being formed at its opposite end with a suitable flange 58 for engagement with a furnace shaft of a 40 conventional type. According to the construction of Fig. 11, a longitudinal slot 59 for the purpose above stated is provided along the length of the rabble arm 52 and is extended to or communicative with a corresponding slot 60 formed along the under 45 side of the adaptor member, so that teeth may be arranged at desired intervals along both members. The transverse sectional views of Figs. 12 and 13 illustrate these 50 parts in further detail. The adaptor member 57, it will be noted, is provided with an internal cooling fluid conduit 61 located along the lower side of the adaptor member in order to properly meet the cooling fluid 55 openings of the furnace shaft, which in this case would be non-concentric.

In Fig. 14 a rabble arm and adaptor construction are shown in a form similar to that of Figs. 11, 12 and 13, but in this instance 60 adaptor member 62 is provided with an internal cooling fluid conduit 63 which is substantially concentrically arranged with the outer shell of the adaptor member for proper engagement with a furnace shaft of 65 slightly different construction. Integral

supporting webs 64 may be provided for properly positioning the conduit member 63 within the adaptor member. Also, according to this construction, a rabble arm member 65 is provided with an internal cooling fluid conduit 66 respectively engaging socket portions within the adaptor member at 67 and 68. According to this construction the rabble arm proper and the adaptor member respectively are provided with independent 75 tooth receiving slots 69 and 70.

According to Fig. 15 a tubular rabble arm member 71 encircles an internal conduit member 72, the member 71 being received within an adaptor member 73 at bearing portions 74 and 75. The internal conduit member on the other hand extends substantially the full length of the adaptor member and is received within a bearing portion 76 at the inner end of the adaptor member. The adaptor member 73 is formed at its inner end for engagement with socket portions on still another form of furnace shaft. The internal conduit 72 is communicative with the inner conduit of the furnace shaft by reason of the opening 77, whereas the space between the tubular members 71 and 72 is communicative with the outer annular space of the furnace shaft by reason of openings as at 78.

In Fig. 16 a construction somewhat similar to that of Fig. 15 is illustrated. In this construction an adaptor member 79 cooperates with a rabble arm member 80, both of said members enclosing an internal cooling fluid conduit 81. At the outer end of the rabble arm a combined end plug and cooling fluid conduit holder 82 is provided. The conduit 81 is of such length as to extend into the furnace shaft into direct communication with the interior conduit thereof, while the adaptor member at a bearing surface 83 engages the outer wall of the furnace shaft. An annular opening at 84 provides communication between the outer space of the furnace shaft and the outer space of the rabble arm and adaptor member. Within the adaptor member the conduit 81 is supported by a bearing portion at 85 cast integral, by reason of web portions 86, with the body portion of the adaptor member. It will be observed that the rabble arm members of the construction of Fig. 15 are interchangeable with the corresponding members of constructions such as shown in Fig. 16.

While the invention has been described in detail with respect to particular preferred examples which give satisfactory results, it will be understood by those skilled in the art, after understanding the invention, that various changes and modifications may be made without departing from the spirit and scope of the invention, and it is intended therefore in the appended claims to cover all such changes and modifications.

What is claimed as new and desired to be secured by Letters Patent of the United States is:

1. A rabble arm comprising a plurality of sections each having individually demountable rabble teeth mounted in fixed position along the sections, and quick-detachable connecting means for the sections. 5
2. A roasting furnace rabble arm having rabble teeth individually mounted in fixed position along the arm, and interchangeable supporting means for said arm whereby a predetermined radius of movement of the teeth is obtainable. 10
3. In a roasting furnace a plurality of rabble arms supported from a rotating shaft for operating in connection with a single hearth, said arms each having rabble teeth individually mounted in fixed position along the arm, said arms being substantially of like construction as regards the position and spacing thereon of rabble teeth, and adaptor members of different lengths for mounting said arms upon said shaft whereby the respective paths of travel of the teeth on the several arms will be interspaced. 15
4. In a roasting furnace a plurality of rabble arms supported from a rotating shaft for operating in connection with a single hearth, said arms being substantially of like construction as regards the position and spacing thereon of rabble teeth, and adaptor members of different lengths for mounting said arms upon said shaft whereby the respective paths of travel of the teeth on the several arms will be interspaced. 20
5. A roasting furnace rabble arm having individually demountable rabble teeth, said arm and teeth having interengaging mortise and tenon portions extending in the general direction of travel of the teeth, but the teeth nearer the supported end of the arm being positioned at progressively increasing angles in respect to such direction of travel, the mortise portions being integrally formed with the body portion of the rabble arm. 25
6. A roasting furnace rabble arm having individually demountable rabble teeth, said arm and teeth having interengaging mortise and tenon portions, the portions on the arm being arranged at various different predetermined angles to respectively affix like teeth at various different desired angles. 30
7. In combination a rabble arm member having its supporting end formed with means for quick-detachable engagement with a supporting socket, and an adaptor for mounting said arm upon a furnace shaft, said arm member, said adaptor and said shaft having communicating cavities for conducting cooling fluid therethrough. 35
8. A roasting furnace rabble arm construction comprising an arm section carrying numerous detachable rabble teeth, and an adaptor member formed with means of a conventional type for engagement with a supporting shaft and formed with socket means of another conventional type for receiving said arm section. 40
9. A roasting furnace rabble arm construction comprising an air cooled arm section carrying numerous detachable rabble teeth, and an adaptor member formed with means for semi-permanent engagement with a supporting shaft and with means for quick-detachable engagement with said arm section. 45
10. A roasting furnace rabble arm construction comprising an arm section formed with a male portion at its supported end, and an adaptor portion formed at one end with provision for bolting to a supporting shaft and at its other end with a female portion for receiving said male portion. 50
11. A roasting furnace rabble arm comprising a plurality of separable arm sections jointed end to end by interengaging plug and socket portions, provision being made within each section and through said interengaging portions for conducting cooling fluid to and from the outer end of the arm. 55
12. A roasting furnace rabble arm comprising a plurality of separable arm sections jointed end to end by interengaging plug and socket portions, one of said sections carrying another of said sections at its outer end. 60
13. A sectional rabble arm comprising a section supported by a rotatable shaft and carrying another section at its outer end, each section of which comprises an inner conduit for cooling fluid surrounded by an outer supporting conduit. 65

In testimony whereof I have signed my name to this specification.

EDWARD J. FOWLER.
